UNITED STATES PATENT OFFICE

BERNHARD HASENSTAB, OF BUFFALO, NEW YORK, ASSIGNOR TO MARKEL ELECTRIC PRODUCTS, INC., OF BUFFALO, NEW YORK, A CORPORATION OF NEW YORK

DESIGN FOR A MEDALLION FOR AN ELECTRIC-LIGHT FIXTURE

Application filed March 14, 1930. Serial No. 34,869. Term of patent 3½ years.

To all whom it may concern:

Be it known that I, BERNHARD HASENSTAB, a citizen of the United States, residing at Buffalo, in the county of Erie and State of New York, have invented a new, original, and ornamental Design for a Medallion for an Electric-Light Fixture, of which the following is a specification, reference being had to the accompanying drawing, forming part thereof.

In said drawing:

Figure 1 is a front elevation of a medallion for an electric light fixture embodying my new design.

Figure 2 is a side elevation thereof.

I claim:

The ornamental design for a medallion for an electric light fixture, substantially as shown.

BERNHARD HASENSTAB.
